DESIGN FOR A COMBINED DIAL AND HANDS FOR A WATCH OR SIMILAR ARTICLE

Augusta L. Scott, Brooklyn, N. Y.

Application March 23, 1938, Serial No. 76,040

Term of patent 14 years

To all whom it may concern:

Be it known that I, Augusta L. Scott, a citizen of the United States, residing at 1953 Troy Avenue, in the county of Kings, city and State of New York, have invented a new, original, and ornamental Design for a Combined Dial and Hands for a Watch or Similar Article, of which the following is a specification, reference being had to the accompanying drawing forming part thereof.

Fig. 1 is a face view of a combined dial and hands for a watch or similar article, showing my new design; and

Fig. 2 is a bottom plan view of the same.

I claim:

The ornamental design for a combined dial and hands for a watch or similar article, as shown.

AUGUSTA L. SCOTT.
